UNITED STATES PATENT OFFICE.

WILLIAM O. COLEMAN, OF INDIANAPOLIS, INDIANA.

LOCK.

1,423,397.

Specification of Letters Patent.

Patented July 18, 1922.

Application filed July 9, 1921. Serial No. 483,582.

To all whom it may concern:

Be it known that I, WILLIAM O. COLEMAN, a citizen of the United States, residing at Indianapolis, in the county of Marion and State of Indiana, have invented new and useful Improvements in Locks, of which the following is a specification.

This invention relates to combination locks, primarily designed for use in connection with safes, the invention residing in the construction, combination, and arrangement of parts as claimed.

In the drawings forming part of this application, like numerals of reference indicate similar parts in the several views and wherein:

Figure 1 shows a rear elevation of a door and a locking mechanism therefor.

Figure 2 is a detail view of the controlling element.

Figure 3 is a vertical sectional view through the safe and door with the latter closed.

Figure 4 is a horizontal sectional view therethrough.

Figure 5 is an enlarged fragmentary view of the controlling element showing the manner in which it is associated with the door for rotary movement.

Figure 6 is an end elevation of the controlling element and the graduated plate in connection therewith.

Figure 7 is a detail view of one of the bolt operating elements.

Referring to the drawings in detail, 10 indicates a safe, the door of which is indicated at 11. The door is of hollow construction defining a compartment 12 for the lock mechanism forming the subject matter of the invention. The mechanism being concealed from view by means of a plate 13 secured to the inner side of the door and forming one wall of the compartment 12.

Arranged within the compartment 12 is a frame-like member in the form of a cross and indicated at 14. It will be noted that all of the shafts and pivots for the different gears are bolt controlling elements and associated with this frame.

Arranged within the compartment 12 are spaced pairs of duplex gears, the gears of one pair being indicated at A, while the gears of the other pair are indicated at B. 55 These gears are adapted to be singly rotated in the manner to be hereinafter de-

scribed through the instrumentality of the controlling element illustrated in Figure 2. This element is in the nature of a bolt 15 which has its shank squared and slideable through a rotatable bearing 16 operating within an opening in the door as clearly illustrated in Figure 5. The outer end of the bolt carries a knob or manipulating element 17, while the inner end of the bolt supports a pinion 18 which meshes with the gears above referred to, to rotate the latter. The controlling element is also guided in its movements by means of spaced parallel toothed guides indicated at 19 in Figure 1, and with which the teeth of the pinion mesh. The bolt 15 is graduated so that its degree of movement can be easily calculated in order to bring the pinion 18 into association with the proper set of gears as the occasion requires.

Each gear of the respective pairs are connected with one of the bolt controlling elements of the character illustrated in Figure 7, wherein it will be noted that each element has a configuration substantially the same as a cross, except that the branch 20 is slightly longer than the branch 21, while the branches 22 are of equal length. Each gear is connected to the long branch 20 of these elements through the instrumentality of a link 23, while connected to the terminals of the remaining branches are reciprocating rods 24, each of which is associated with a locking bolt 25 which is adapted to be projected through aligned openings in the door 11 and the safe 10. Manifestly, each gear controls the operation of three of these bolts. It will be further noted that the bolt controlling elements are mounted upon the frame 14 in pairs, the elements 17 of each pair being disposed one in advance of the other.

Upon inspection of Figure 4, it will be noted that the teeth 26 of the gears A are disposed in alinement, but these teeth of each gear are interrupted as at 27 for a purpose to be hereinafter described. The teeth 28 of one of the gears A are disposed slightly in advance of the corresponding teeth 28 of the other gear A, so that the pinion 18 can be arranged to mesh with the teeth 28 of the respective gears singly. The teeth 29 of one gear B is also arranged out of alinement with the corresponding teeth 30 of the other gear B, for the same purpose just stated, that is to permit the pinion 18

to mesh with the teeth 29 and 30 of the respective gears to singly rotate the latter. The teeth 31 of the gears B are arranged in alinement and are also interrupted in the 5 same manner as the teeth 26 of the gears A.

In practice, the controlling element 15 together with its pinion 18 slides through the bearing 16 and through the space between the group of gears as shown in Figure 4. In Figure 1, the bolts 25 are all extended to their locking position, and the pinion 18 of the controlling element is positioned between the interrupted portions 27 of the teeth 26 of the gears A, so that 10 should the controlling element be rotated in either direction, the pinion 18 would remain free of the gears A and in no way effect the lock mechanism. However, when it is desired to unlock the safe, the controlling 15 element 15 is moved outwardly through its bearing 16, until the pinion 18 meshes with the teeth 28 of one of the gears A, whereupon the controlling element is rotated a predetermined distance which may be calculated by the graduated plate 32 in the usual manner. When the actuating element has been rotated in this manner, one of the gears A is actuated to impart movement to the particular bolt controlling element with 20 which it is associated, moving this element upon its pivot in a direction to retract the three locking bolts which is controlled by said element. The controlling element is then moved outwardly of the door through 25 the bearing 16 until the pinion 18 is brought in a position to mesh with the corresponding teeth of the other gear A, whereupon the bolt is again rotated in a proper direction to impart movement to the particular bolt 30 controlling element with which it is associated. Consequently, three more of the locking bolts 25 are retracted to their inactive 35 positions. The controlling element is then again moved through the bearing 16 until 40 the pinion is brought into mesh with the teeth 29 of one of the gears B, whereupon the bolt is again rotated a predetermined distance to retract three more of the locking bolts, which are controlled by the cross-shaped element associated with this particular gear. The controlling element is finally 45 moved to bring the pinion 18 into mesh with the teeth 30 of the remaining gear B, whereupon the bolt is rotated to retract the remaining three locking bolts 25 in the manner 50 above stated. The door is then unlocked, so that it can be swung upon its hinges to an open position and access had to the safe.

In order to lock the safe, the controlling 55 element 15 is passed inwardly through the bearing 16, bringing the pinion 18 into mesh with the gears 26. By turning the controlling element in either direction, these gears 60 are simultaneously rotated and project six of the bolts to active position. The pinion

18 is then brought into mesh with the gear 65 31, and in turning the controlling element in either direction, the other bolts are projected. The construction and operation of the mechanism is such that it would be impossible for anyone to control the locking 70 bolts in groups as above described, unless they were familiar with the particular combination and the manner of using the controlling element 15.

While it is believed that from the foregoing description the nature and advantages of the invention will be readily apparent, I desire to have it understood that I do not limit myself to what is herein shown and 75 described, and that such changes may be resorted to when desired as fall within the scope of what is claimed.

What I claim is:

1. A combination lock mechanism including a plurality of locking bolts connected in groups, each group being movable independently of the other groups, spaced pairs of gears, a connection between each gear and one group of said bolts, a controlling element 80 mounted for both sliding and rotary movements, and a pinion carried by said element and adapted to mesh with each gear, whereby said groups of bolts are singly controlled.

2. A combination locking mechanism including a plurality of locking bolts connected in groups, each group being movable independently of the other group, spaced pairs of duplex gears, a connection between each gear and one group of said bolts, a controlling element mounted for both sliding and rotary movements between the respective pairs of said gears, a pinion carried by said element, and the corresponding innermost teeth of each pair of gears being arranged out of alinement, whereby said pinion may mesh and operate each gear singly to control one group of said bolts as described.

3. A combination lock mechanism including a plurality of locking bolts connected in groups, each group being movable independently of the other groups, spaced pairs of duplex gears, a controlling element mounted for both sliding and rotary movements in the space between said gears, a connection between each gear and one group of said bolts, a pinion carried by said controlling element, the innermost corresponding teeth of each pair of gears being arranged out of alinement, whereby said pinion may singly actuate said gear to control one group of bolts, and the corresponding outermost teeth of each pair of gears being interrupted, and adapted to have their interrupted portions oppositely disposed for the purpose specified.

4. A combination lock mechanism including a plurality of locking bolts connected in groups, the connecting element for each

group including a plurality of branches, one of which is associated with one bolt of said group, one group of bolts being movable independently of the other groups, spaced 5 pairs of gears, a link joining each gear with one of said connecting elements, a lock controlling element mounted for both sliding and rotary movements, and a pinion carried by said element and adapted to mesh with each gear singly, whereby said groups of the 10 bolts are independently controlled.

In testimony whereof I affix my signature.

WILLIAM O. COLEMAN.
